UNITED STATES PATENT OFFICE.

ALFRED ELEY PRESTON, OF LOOE, ENGLAND.

MOVABLE KEEL FOR BOATS.

SPECIFICATION forming part of Letters Patent No. 663,982, dated December 18, 1900.

Application filed June 11, 1900. Serial No. 19,899. (No model.)

To all whom it may concern:

Be it known that I, ALFRED ELEY PRESTON, a subject of the Queen of Great Britain and Ireland, residing at St. George's Island, Looe, 5 Cornwall, England, have invented certain new and useful Improvements in Movable Keels for Ships, Yachts, Boats, Canoes, and the Like, of which the following is a specification.

This invention relates to movable keels for 10 ships, yachts, boats, canoes, and the like, and provides a keel which can be collapsed or extended in a simple manner and which will present a smooth surface to the water.

The apparatus comprises three main parts— 15 two arms or plates and a heavy weight connecting them together at the bottom. The two arms carrying the weight are pivoted to fixed parts on the boat, and these pivots are placed in a line parallel with the points of 20 suspension of the weight, the distance between the points and pivots being also equal. The arms and weight thus form a jointed parallelogram which insures the weight moving parallel to itself, keeping it horizontal in all 25 positions of the arms. The front arm or plate is of considerable width, presenting a large surface to the water, and this arm is double, allowing the narrow arm to lie within it, the edge presented to the water being rounded 30 and offering a comparatively small resistance. Both arms extend above their pivoted points for some distance and are connected by a link. They are pulled up within the centerboard-case by a windlass or like device, the rope or 35 chain of which is attached to the upper end of the front plate. On pulling in the keel the parts all collapse within the centerboard-case, but drop into extended position when released.

In order that this invention may be more 40 readily understood, reference is had to the accompanying sheet of drawings, in which—

Figure 1 is a longitudinal section of a boat, showing the keel in extended position. Fig. 2 is a similar view with the keel collapsed 45 within the boat. Figs. 3 and 4 are cross-sections showing the keel extended and collapsed, and Fig. 5 is an under side view of the boat with the keel raised.

A is the main plate or body of the keel, pivoted at a to the boat. This plate is doubled, as shown in Figs. 3, 4, and 5, and its front edge a' is closed, supplying a narrow smooth

edge, which cuts through the water with small resistance.

The rear arm or plate B lies within the 55 double plate A, so that it does not interfere in any way with the action of the apparatus and does not add to the resistance. This arm is pivoted at b to the bracket B', which projects between the sides of the main plate 60 A, and the pivot b is at the same level as a , which may also be carried by the bracket B'. To the lower end of both arms the weight C is attached at the points c parallel to a and b and at the same distance apart. The points 65 a , b , c , and c thus form a parallelogram, and as these are all pivots the arms can collapse or extend, keeping the weight C always horizontal. The weight C is sufficient to keep this keel fully extended against the force of 70 the water through which the boat D is moving, or it may be fixed down by a movable pin in the centerboard-case.

Both arms or plates A and B are extended at a' and b' into the centerboard-case d, and they are connected together at their upper ends by the link E, and the rope or chain F is attached to the upper end of the plate A, passing to a winch f. By this means the keel is collapsed within the centerboard-case 80 d, as shown especially in Figs. 2 and 4, while it can be lowered fully or to any intermediate position by the same means.

The apparatus can be entirely removed from the boat through the centerboard-case, 85 which may be open at the top, or it may be removed from the bottom of the boat, as found most convenient.

What I claim as my invention, and desire to secure by Letters Patent, is—

1. An improved movable keel for boats, comprising a large double front plate pivoted at the bottom of the boat, a second arm or plate also pivoted lying between the sides of the front plate, a weight connecting both 95 plates at the lower end forming with their pivots a jointed parallelogram, and means for collapsing the keel within the centerboard-case, substantially as described and for the purposes specified.

2. In a movable keel for boats, the combination of a double plate A pivoted at a , a pivoted plate B lying within the double plate, the bracket B' to which the plate B is fitted,

the weight C attached to the plates A and B at the points c, the link E connecting the plates at their upper ends and connections to the upper ends of the plates by which the 5 keel can be collapsed within the boat, substantially as herein described and shown.

In testimony that I claim the foregoing as

my invention I have signed my name in presence of two subscribing witnesses.

ALFRED ELEY PRESTON.
